UNITED STATES PATENT OFFICE.

RICHARD G. INWOOD, DECEASED, LATE OF SOUTH BEND, INDIANA, BY MARY CAIN INWOOD, ADMINISTRATRIX, OF SOUTH BEND, INDIANA, ASSIGNOR TO WIRE-BOUNDS PATENTS COMPANY, OF KITTERY, MAINE, A CORPORATION OF MAINE.

BOX-MAKING MACHINE.

1,425,774.

Specification of Letters Patent. Patented Aug. 15, 1922.

Application filed January 10, 1918, Serial No. 211,264. Renewed February 4, 1922. Serial No. 534,259.

To all whom it may concern:

Be it known that RICHARD G. INWOOD, deceased, late a citizen of the United States, and resident of South Bend, in the county of St. Joseph and State of Indiana, has invented an Improvement in Box-Making Machines, of which the following is a specification.

This invention relates to machinery for making wire bound boxes and the like. More particularly it pertains to means for severing binding wire which has been secured to box or similar parts.

For purposes of illustration, the invention will be described as embodied in a machine for making wire bound box blanks, the principal object of the invention, when embodied in such a machine, being to sever the binding wires between one blank and the next after the wires have been attached to the blanks. Obviously the invention is not limited, in its application, to machines of this particular type.

In the drawings:

Fig. 1 is an end elevation of the illustrative machine as viewed from the left in Fig. 2;

Fig. 2 is a side elevation of that end of the machine shown in Fig. 1 as viewed from the right in Fig. 1;

Fig. 3 is a detailed side elevation of certain of the wire severing devices;

Fig. 4 is a section on the line 4—4 of Fig. 3;

Fig. 5 is a detached detail side elevation of certain other cutting devices;

Fig. 6 is an end elevation of the parts shown in Fig. 5 as viewed from the right in Fig. 5.

The specific type of wire bound box blank machine selected for illustration is intended for making box blanks comprising cleats, side sheets and binding wire, the three being secured together by staples which straddle the binding wire, pass through the side sheets and anchor in the cleats. To suit this particular object, the machine is provided with a work holder and conveyor which receives the cleats and sheets, holds them in proper relationship, and introduces them to binding-wire feeding and staple driving mechanism which lays the binding wire on the box

parts and staples it to them. Ordinarily, when made upon such a machine each wire bound box blank comprises four sections for the top, bottom, front and rear sides of the box; and the machine is adapted to apply continuous lengths of binding wire to a succession of these sections. The binding wires are intended to be severed between one box blank and the next in such manner as to leave free ends of the wire projecting beyond each end of the blank so that when the blank is folded into box form these projecting wire ends will meet to be twisted together for closing the box. To suit this purpose, the work positioning means on the conveyor is constructed to space the rear end of one blank at a substantial distance from the advance end of the next following blank to allow between them a sufficient length of wire to supply, when severed, the desired free ends.

The particular embodiment of the invention selected for illustration has for its purpose to sever the wire between the box blanks for the purposes just described.

Referring to the drawings:—The work conveyor comprises endless chains 10—11 mounted upon sheaves 12 and moved intermittently in the direction of the arrow 13 in Fig. 2, by means of any suitable mechanism such as the pawl and ratchet mechanism illustrated in Fig. 2.

Binding wire 14 is fed from a convenient source into proper relationship with the work on the conveyor 10; and during the periods of rest of the conveyor, staples are driven astride of the binding wire and into the sheets and cleats (where the cleats are present) or simply into the sheets where no cleats are present. A vertically reciprocating cross-head 15 carries suitable driving mechanism of any suitable type, unnecessary to be shown.

It is assumed that the illustrative machine is adapted to apply four binding wires to a succession of box blanks. One wire is applied in alignment with the conveyor 10 which carries a row of cleats; and another applied in alignment with the conveyor 11 which carries a second row of cleats; two other wires are applied at intermediate points as presently described.

Referring now to Fig. 3, the rear end of

one box blank is shown at the left as comprising a cleat 16 and a sheet 17 while the advance end of another box blank is shown at the right, comprising a cleat 18 and sheet 19. A binding wire 14 is shown extending over and between these two blank ends and secured to them respectively by staples 21 and 22. The blank ends are spaced apart a desired distance by means 5 of a spacer block 23 which in the illustrative embodiment of the invention serves also as a part of the wire severing mechanism.

A spacer block 23 is secured in any suitable manner to each of the conveyors 10 and 11; and each conveyor may have a number of spacer blocks 23 corresponding to the number of blanks which the conveyor is constructed to carry. The particular spacing block 23 is secured to its conveyor by being bolted to a flange of the conveyor chain as indicated in Fig. 1.

As shown in Fig. 4, the spacer block 23 is recessed at 25 to provide a seat for the wire 14 in which the wire may rest during the severing operation.

Adjacent this seat 25, the block 23 is recessed to leave a face 26, the intersection of the seat 25 and the face 26 providing a cutting edge against which the wire may be severed in cooperation with the devices next described.

Near each conveyor, and directly above the path of the spacer blocks 23, is a cutting wheel 28 having one or more cutting blades 29. The wheels 28 are mounted upon a shaft 30, and the path of rotation of each blade 29 (as indicated by the dash line in Fig. 3) intersects the path of the cutting edge on the face 26 of the spacer block 23. The position of rest of the cutting wheel 28 is shown in Fig. 3, and therein the blade 29 stands in position to contact with the face 26 of the cutting block 23 as the latter is moved toward the left in Fig. 3 during the feeding movement of the work conveyor. Thus, as the spacer block 23 moves toward the left in Fig. 3, it will presently contact with the blade 29 and will forcibly rotate the cutting wheel 28 and shaft 30, thereby moving the blade 29 from the position shown in Fig. 3 to the position of the blade 32, in which position the face 26 of the spacer block will leave the cutter wheel 28, to await the arrival of another spacer block in the further feeding movement of the conveyor. Obviously, as the face 26 of the spacer block 23 strikes and rotates the blade 29, it forces the cutting edge of the blade downwardly 55 so that the edge cooperates with the cutting edge of the spacer block to sever the wire.

It will be evident that the cutting operation and the point at which the wire is severed are conveniently determined by the position of the face 26 of the spacer block

23, in relation to the wire, and therefore the point at which the wire is cut may be very definitely predetermined by the particular construction of the spacer block 23. For instance, that part of the spacer block 23 which intervenes between the face 26 and the advance end of the sheet 19 of the rear box section serves in effect as a gauge which may definitely measure and predetermine the length of wire which is to be left projecting beyond the end of the box blank. Similarly, that part of the spacer block 23 which intervenes between the face 26 and the rear end of the sheet 17 of the advance box blank serves as a gauge to predetermine the length of wire to be left projecting from the rear end of said blank.

One of the cutter wheels 28 is fixed upon the shaft 30 opposite each of the conveyors 10 and 11. It should be borne in mind that in this specific embodiment of the invention the movement of the spacer blocks 23 during the feed of the conveyor, provides the power which rotates the cutter wheels 28 and shaft 30 so that it is the movement of the work which causes the occurrence of the cutting operation.

Since there are preferably no conveyors, such as chains 10 and 11, at intermediate points transversely of the blank, and therefore no convenient means of providing spacer blocks 23 or similar devices to assist in severing the intermediate wires, a somewhat different expedient is adopted for this purpose.

A cutter wheel 35 is mounted on the shaft 30 in position to act upon each of the intermediate binding wires; and registering with each cutting wheel 35 is a second cutting wheel 36 fixed upon a shaft 37.

The shafts 30 and 37 are geared together to rotate in opposite directions at the same speed. For instance, the shaft 30 has a fixed gear 40 driving an intermediate gear 41 on a short shaft, which in turn drives a gear 42 on a shaft 43 having another gear 44 which drives a gear 45 on the shaft 37.

These gears 40, 41, 42, 44, and 45 are all of the same size. Thus, when the feed of the work, acting through the spacer block 23 aforesaid rotates the cutter wheel 27 and its shaft 30, the cutter wheels 35 and 36 are likewise forcibly rotated, their progressive relationships being indicated by dotted lines in Fig. 5. Each cutting blade on the cutter wheels 36 has a wire-seat 48 and a face 49, the intersection of the two providing a cutting edge, as in the case of the spacer block 23.

As shown in Figs. 3 and 5, the cutter wheels 28 and 35 are in their positions of rest during which they stand idle and in such position that the box blanks may pass freely beneath them. It will be noted that there is sufficient clearance between the cut-

ter wheel 35 and the cutter wheel 36 when they are in their positions of rest as shown in full lines in Fig. 5, to permit the wired side sheets of a box section to pass freely between them.

It is usual in machines of the type described to have the conveyors and other corresponding parts adjustable toward and from each other (i. e., transversely of the 10 box blanks) to suit blanks of different widths. The binding wire feeding and staple driving units are similarly adjustable to place both the outside and the intermediate wires in proper positions. To suit this character of adjustment, the various cutting wheels described above may be made adjustable lengthwise of their respective shafts, as by having a keyway cut along the length of the shaft and keys projecting from the 15 cutting wheels into the ways permitting the cutter wheels to be moved lengthwise of the shafts and held in adjusted position by set screws in their hubs.

It is to be understood that this invention 25 is not limited to the particular embodiment shown and described herein for illustration; on the contrary, the invention may be variously embodied and the particular construction shown may be variously modified as 30 will appear to those skilled in the art.

What is claimed is:—

1. A machine for use in making wire-bound boxes comprising, in combination, fastener driving means for securing binding 35 wire to box parts; movable means for relatively moving the fastener driving means and box parts to apply fasteners at different points on the box parts; and wire severing means directly operable by the movable means in its movement.

2. A machine for use in making wire-bound boxes comprising, in combination, fastener applying means for securing binding wire to box parts; means for feeding 45 box parts in relation to said fastener applying means; and wire severing means directly operated by the box part feeding means in its feeding movement.

3. A machine for use in making wire-bound boxes comprising, in combination, fastener applying means for securing binding wire to box parts; means for feeding box parts in relation to the fastener applying 50 means; binding wire severing devices; and actuating means for the binding wire severing devices operable during the feeding movement of the box parts.

4. A machine for use in making wire-bound boxes comprising, in combination, 60 fastener applying means to secure binding wire to box parts; a conveyor to present box parts to the fastener applying means; means for relatively moving the fastener applying means and conveyor to present to the former 65 different portions of a box part; and wire

severing means directly operated by said conveyor.

5. A machine for use in making wire-bound boxes comprising, in combination, fastener applying means to secure binding 70 wire to box parts; work holding means to present box parts to the fastener applying means; wire severing means; and gauging means, positioned in the desired relation to a box part to definitely determine the point 75 at which the wire is to be severed relative to said box part, regardless of irregularities in the movements of the box parts.

6. A machine for use in making wire-bound boxes comprising, in combination, 80 fastener applying means for securing binding wire to box parts; means for feeding box parts in relation to the fastener applying means; and wire severing means movable with the binding wire during the severing 85 operation.

7. A machine for use in making wire-bound boxes comprising, in combination, fastener applying means for securing wire 90 to a box part; work holding means to present a box part to the fastener applying means; a gauge carried by the work-holding means to measure the length of wire relative to the edge of a box part; and wire severing means to sever the wire at the point pre-determined by said gauge regardless of 95 irregularities in the movements of the box parts.

8. A machine for use in making wire-bound boxes comprising, in combination, 100 means to secure binding wire to box parts; means to cause relative movement between said wire-securing means and successive pieces of work; a spacer block between such pieces of work; and wire severing means 105 directly actuated by said spacer block.

9. A machine for use in making wire-bound boxes comprising, in combination, fastener applying means for securing wire 110 to box parts; a conveyor for the box parts; wire severing means on the conveyor; and additional wire severing means co-operating with those on the conveyor.

10. A machine for use in making wire-bound boxes comprising, in combination, 115 fastener applying means to secure wire to box parts; a conveyor for the box parts; a wire severing wheel to sever wire after it is secured to a box part; and means on the conveyor for causing said wheel to sever the 120 wire.

11. A machine for use in making wire-bound boxes comprising, in combination, fastener applying means to secure wire to box parts; a plurality of successively acting 125 wire severing devices to act upon wire after it is secured to the box parts; means for relatively moving the box parts and wire-severing means; and means for causing operation of the wire severing means at a plu- 130

- rality of predetermined points in the said relative movement without stopping the machine.
12. A machine for use in making wire-bound boxes comprising, in combination, 5 fastener applying means for securing wire to box parts; an endless chain conveyor for the box parts; a wire severing wheel located above each wire secured to a box part; and means beneath each said wire to co-operate with the severing wheel.
13. The combination of work holding means to hold wired box parts or the like with gauging means in predetermined relationship to the work in said holder, to predeterminedly determine the point of severing of the wire; and wire severing means co-operating with said gauging means to sever the wire at said point.
14. The combination of a work holder to hold wired parts of boxes or the like; wire severing means; and means for causing the wire severing means to sever the wire on a box part in said holder solely by movement 25 of the holder.
15. The combination of a work holder for a wired box part; a positioning device on the work holder for positioning a portion of the box part; a cutting edge on said positioning device; and means for severing the wire against said cutting edge.
16. A wirebound box blank machine comprising, in combination, a plurality of staple driving mechanisms for stapling binding wire to a succession of box blanks; means to cause relative movement between a succession of box blanks and the stapling devices; a series of cutting devices corresponding respectively to the stapling devices and located in the rear of the latter, for severing binding wires after they are secured to a succession of box blanks; and means directly actuated by relatively moving the work and staple driving mechanisms to actuate the wire severing means.
17. A machine for use in making wire-bound boxes comprising, in combination, means to secure binding wire to box parts; means operable solely by relatively moving the box parts and wire-securing means to sever said binding wire; and means for relatively moving the box parts and wire-securing means.
18. A machine for use in making wire-bound boxes comprising, in combination, 55 means to secure binding wire to box parts; means for feeding box parts in relation thereto; and means directly operated by the feeding movement of the box parts to sever said binding wire.
19. A machine for use in making wire-bound boxes comprising, in combination, means to secure binding wire to box parts; means directly operable by relatively moving the box parts and wire-securing means
- to sever said binding wire; and means for effecting such relative movement; the operation of said wire-severing means dependent upon a predetermined extent of such relative movement.
20. A machine for use in making wire-bound boxes comprising, in combination, 70 means to secure binding wire to box parts; means for relatively moving the box parts and wire-securing means; and cutting means directly operable by said relative movement arranged to sever the binding wire at a predetermined point.
21. A machine for use in making wire-bound boxes comprising, in combination, 80 means to secure binding wire to box parts; means to cause relative movement between said wire-securing means and box parts; and wire-severing means directly actuated by said relative movement.
22. A machine for use in making wire-bound boxes comprising, in combination, 85 means to secure binding wire to box parts; means to cause relative movement between said wire-securing means and box parts; and wire-severing means controlled and directly actuated by said relative movement.
23. A machine for use in making wire-bound boxes comprising, in combination, 90 means to secure binding wire to box parts; means for relatively moving the box parts and wire-securing means; and means to sever the binding wire during such movement.
24. A machine for use in making wire-bound boxes comprising, in combination, 100 means to secure binding wire to box parts; means for moving the work relative thereto; and automatic wire-severing means movable with the work.
25. A machine for use in making wire-bound boxes comprising, in combination, 105 means to secure binding wire to box parts; means for feeding box parts relative thereto; and wire-severing means operating to sever the binding wire during the feeding movement of the box parts.
26. A machine for use in making wire-bound boxes comprising, in combination, 110 means to secure binding wire to box parts; means for moving the work relative thereto; and automatic wire-severing means movable with the work during the severing operation.
27. A machine for use in making wire-bound boxes comprising, in combination, 115 means to secure binding wire to box parts; means to cause relative movement between said securing means and box parts; and wire severing means moving with the wire during a severing operation.
28. A machine for use in making wire-bound boxes comprising, in combination, 120 means to secure binding wire to box parts; means to cause relative movement between said securing means and box parts; and wire severing means moving with the wire during a severing operation.
- 130

said securing means and box parts; and wire severing means moving with the work during a cutting operation and controlled in accordance with said relative movement.

5 29. A machine for use in making wire-bound boxes comprising, in combination, means to secure binding wire to box parts; means to cause relative movement between said securing means and the box parts; and 10 wire severing means movable during a cutting operation in accordance with said relative progression.

30. A machine for use in making wire-bound boxes comprising, in combination, 15 means to secure binding wire to box parts; means to cause relative progression between said securing means and the box parts; and means to cut said wires between box parts at a definitely selected point relative to 20 edges of each of said box parts regardless of irregularity of said relative progression.

31. A machine for use in making wire-bound boxes comprising, in combination, means to secure binding wire to box parts; 25 means to feed box parts relative to said securing means; and means movable with the work during a severing operation to cut the wires at selected points between box parts.

30 32. A machine for use in making wire-bound boxes comprising, in combination, means to secure binding wire to box parts; means to feed box parts relative to said securing means; and means movable with the 35 work and controlled in accordance with its movement to cut the wires at selected points between box parts.

33. A machine for use in making wire-bound boxes comprising, in combination, 40 means to secure binding wire to box parts; means to feed box parts relative to said securing means; and means movable with the work and controlled in accordance with its movement to cut the binding wire at a selected point between box parts, including 45 gauging means determining such point.

34. A machine for use in making wire-bound boxes comprising, in combination, 50 means to secure binding wire to box parts; means for relatively moving the box parts and wire-securing means; and means directly actuated by said moving means and controlled in accordance with said relative movement to sever the binding wire at a predetermined point.

35. A machine for use in making wire-bound boxes comprising, in combination, 55 work-positioning means; means to secure binding wire to box parts; means to cause relative movement between said securing means and box parts; and wire-severing means controlled and directly actuated by the work positioning means.

36. A machine for use in making wire-bound boxes comprising, in combination, 60

means to secure binding wire to box parts; means for relatively moving the box parts and wire-securing means; and automatic wire-severing means comprising cooperable cutting members, one in fixed relation to a 70 box part and another brought into coaction therewith by said relative movement.

37. A machine for use in making wire-bound boxes comprising, in combination, 75 means to secure binding wire to box parts; means for feeding box parts relative thereto; and automatic wire-severing means including a rotary cutter; said machine being adapted to operate without interruption upon materials for a plurality of boxes. 80

38. A machine for use in making wire-bound boxes comprising, in combination, means to secure binding wire to box parts; means to cause relative progression between said securing means and the box parts; and 85 wire-severing means comprising a pair of cutting members adapted to be brought into operating engagement solely by said relative progression.

39. A machine for use in making wire-bound boxes comprising, in combination, means to secure binding wire to box parts; means to cause relative progression between said securing means and the box parts; and wire-severing means comprising a pair of 95 independent members adapted to engage the wire between them and move therewith during a cutting operation.

40. A machine for use in making wire-bound boxes comprising, in combination, 100 means to secure binding wire to box parts; means to cause relative progression between said securing means and the box parts; and wire-severing means comprising a pair of 105 independent members one of which is actuated by the relative movement and engages and operates the other member.

41. A machine for use in making wire-bound boxes comprising, in combination, 110 means to secure binding wire to box parts; means to cause relative progression between said securing means and the box parts; and wire-severing means comprising a pair of cutting members having provision for relative progression therebetween and adapted 115 to cooperate and move with the wire during a cutting operation.

42. A machine for use in making wire-bound boxes comprising, in combination, 120 work-forwarding means; binding-wire-applying mechanism; and wire-severing mechanism directly actuated by the work-forwarding means.

43. A machine for use in making wire-bound boxes comprising, in combination, 125 work-forwarding means; binding-wire-applying mechanism; and wire-severing mechanism controlled and directly actuated by the work-forwarding means.

44. A machine for use in making wire- 130

- bound boxes comprising, in combination, work-forwarding means including cutter-gauging means; fastener-setting mechanism; and wire-severing mechanism directly actuated by the gauging means. 5
45. A machine for use in making wire-bound boxes comprising, in combination, work-forwarding means; fastener-setting mechanism; and wire-severing mechanism including a cutting member in fixed relation to the work and movable therewith. 10
46. A machine for use in making wire-bound boxes comprising, in combination, work-forwarding means; fastener-setting mechanism; and wire-severing mechanism including a cutting member carried by the work-forwarding means. 15
47. A machine for use in making wire-bound boxes comprising, in combination, a circulating conveyer for the box parts; means to secure binding wire to the box parts; and wire-severing means including a cutting member adapted to circulate with the conveyor. 20
48. A machine for use in making boxes comprising, in combination, work-feeding means, mechanism for applying binding wire to box parts, and wire-severing means adapted to enter spaces between box parts 25 and move therewith during a cutting operation. 30
49. A machine for use in making boxes comprising, in combination, work-feeding means, mechanism for applying binding wire to box parts, and wire-severing means operable by movement with the work. 35
50. In a machine for use in making wire-bound boxes, the combination of mechanism to secure binding wire to box parts, means 40 to cause relative progression between said mechanism and the work, and a wire cutter comprising a plurality of movable knives operable upon movement of said cutter in the direction of travel of the work. 45
51. A machine for use in making boxes comprising, in combination, work-feeding means, mechanism for applying binding wire to box parts, and wire-severing means adapted to enter spaces between box parts comprising cutting members automatically operable by movement of said wire-severing means longitudinally of the work. 50
52. A machine for use in making wire-bound boxes comprising, in combination, work-forwarding means; mechanism to apply binding wire to box parts; and wire-severing means comprising a plurality of relatively movable cutting members operable in spaces between box parts through direct actuation by the work-forwarding means. 60
53. A machine for use in making wire-bound boxes comprising, in combination, work-forwarding means; mechanism to apply binding wire to box parts; wire-severing means adapted to enter spaces between box parts and be actuated by the work-forwarding means; and gauging means for definitely determining the point of cut-off relative to box part edges regardless of irregularities in the movement of the box parts. 65
54. A machine for use in making boxes comprising, in combination, work-forwarding means; binding-wire-applying mechanism; and wire-severing means adapted to enter spaces between box parts and be directly actuated by the work-forwarding means. 70
55. A machine for use in making boxes comprising, in combination, work-forwarding means; binding-wire-applying mechanism; and a plurality of wire-severing mechanisms adapted to enter spaces between box parts and be directly actuated by the work-forwarding means. 75
56. A machine for use in making boxes comprising, in combination, work-forwarding means; binding-wire-applying mechanism; and a plurality of wire-severing mechanisms normally held in inoperative position but adapted upon presentation of a space 80 between box parts to enter said space and be directly actuated by the work-forwarding means. 85
57. A machine for use in making wire-bound boxes comprising, in combination, binding-wire-applying mechanism; means to cause relative progression between said mechanism and the work; and wire-severing mechanism including relatively movable cutting members normally located respectively 90 above and below a wire and adapted to operate upon movement with the wire. 95
- In testimony whereof, I have signed my name to this specification.
